COMBINED BOTTLE AND CLOSURE THEREFOR

Olof Verner Anderson, North Kingston, R.I., assignor to Anson, Inc., Providence, R.I., a corporation of Rhode Island

Filed Sept. 1, 1965, Ser. No. 86,800

Term of patent 14 years

(Cl. D58—8)

The characteristic feature of my design resides in the combination on the reverse tapered bottle disclosed of the specific oversized, domed cap having a flat surface separating the concave sides and the curved top, all as shown.

I claim:

The ornamental design for a combined bottle and closure therefor, as shown and described.
